JULIUS C. WALK, OF INDIANAPOLIS, INDIANA, ASSIGNOR TO BINGHAM & WALK, OF SAME PLACE.

DESIGN FOR A SPOON.

SPECIFICATION forming part of Design No. 21,079, dated September 29, 1891.

Application filed April 28, 1891. Serial No. 390,837. Term of patent 3½ years.

To all whom it may concern:

Be it known that I, JULIUS C. WALK, a citizen of the United States, residing at Indianapolis, in the county of Marion and State of Indiana, have invented and produced a new and original Design for Spoons, of which the following is a specification.

As shown in the accompanying drawing, the leading features of my design consist in the representation of a monument and a vignette showing a buffalo and a man chopping down a tree, the remainder of the spoon being generally suitably formed and ornamented to produce a pleasing whole.

What I claim is—

The design for a spoon embodying a representation of a monument, and also a representation of a buffalo and a man chopping down a tree.

In witness whereof I have hereunto set my hand and seal, at Indianapolis, Indiana, this 25th day of April, A. D. 1891.
